COIL WINDING MACHINE

Lowell M. Mason, Fort Wayne, Ind., assignor to General Electric Company, a corporation of New York

Application November 12, 1953, Serial No. 391,496

39 Claims. (Cl. 140—92.1)

This invention relates to coil winding machines, and more particularly to a novel machine for winding coils into the slots of electric motor stators.

Where stator coils have been wound by machine, it has been customary to have the machine wind the coils directly into the stator slots, that is, the coils are actually wound in the slots without any previous forming. Several undesirable factors have presented themselves in winding machines using this kind of operation. These stem mainly from the fact that the winding cannot be an accurate operation since it would be highly impractical to use any kind of form in the slots themselves. One result of this inaccuracy is that a smaller number of turns can be introduced into each slot than would be the case if the coils were accurately placed to take up no more space than was necessary. A corollary to this objection is that most machines in use today produce cross overs on the wires, that is, the wires cross over each other and take up more room. Quite frequently this results in the coating of insulation being cracked or broken, particularly in the slots. Another objection to winding the coils directly in the slots is that an unnecessary amount of time is consumed, since each winding has to be put into each slot turn by turn. Yet another undesirable result of performing the winding operation directly in the slots is that high pressure points frequently occur between the wire and the corners of the slots, bringing about the likelihood of damaging the slot insulation.

To avoid these undesirable features it is necessary to eliminate the winding operation in the slots. To achieve precision, economization of space, and speed it is necessary to provide a machine which will prewind the coils and then place these prewound coils in the stator slots. Since these are two entirely separate operations, such a machine will be able to be in the process of winding another coil while an already wound coil is being inserted into the stator slots. Furthermore, the winding forms can be so made that all available space in the slots is used so that cross overs of wires are eliminated.

An object of this invention is, therefore, to provide a coil winding machine which will pre-wind the coils and then, in a separate operation, insert them into the stator slots.

A further object of this invention is to provide a coil winding machine which will eliminate the above named undesirable features through fast precise operation.

Further objects and advantages of this invention will become apparent and the invention will be better understood by reference to the following description and the accompanying drawings; and the features of novelty which characterize this invention will be pointed out with particularity in the claims annexed to and forming a part of this specification.

This invention in its broadest aspects provides a coil winding machine which will pre-wind the coils and then place them in the field member slots. Means are provided for winding the coils around stationary forms, and other means strip the coils off the forms and place them

2

in a member which then carries the coils to the field member and inserts them into the slots.

In the drawings,

Referring now to Figures 1 and 2 of the drawings, the sequence of operation of the machine will be shown. All parts referred to in this first brief description will be more fully described subsequently. A pair of motors 1

60 and 2 rotate in opposite directions. By means of pulleys 3 and 25, belts 4 and 26, pulleys 5 and 24 and a clutch 6, pulley 82 and V belts 98 will be caused to rotate in one direction or the other. A pedal 9 will, when operated, actuate a linkage assembly 10 to operate clutch 6. Coil wire 11 feeds from a spool (not shown) and passes over tensioning wheels 12 and is fed over wheel 13, under wheel 14 and through the housing 15 to carriage 16. Carriage 16 is mounted on a guide 17 which rotates about coil form 172 which is stationary. Lead screws 159

65 and 160 rotate relative to guide 17 to cause carriage 16 to move longitudinally along guide 17. By this means carriage 16 carries the wire around coil form 172 to form

the coils. When the coils have been formed, they are removed from form 172 by means to be later described, and placed in injection head 20. Injection head 20 moves at right angles to the axis of coil form 172 and is operated by a gear motor 21 whose operation is timed by a switch 22 controlled by a pair of cams 23. By means of motor 21, projection head 20 moves the coils over to the stator core and inserts the coils in the slots thereof.

Referring now to Figure 20 of the drawings, electric motor 1 rotates in a clockwise direction while motor 2 rotates in a counterclockwise direction. Both motors 1 and 2 operate continuously during use of the machine. Motor 1 transmits its clockwise motion to a pulley 24 through pulley 25 and belt 26. Motor 2 transmits its counterclockwise motion to pulley 5 by means of pulley 3 and belt 4.

When it is desired that a coil winding operation be performed the machine operator applies momentary pressure with his foot to bar 28 of foot pedal 9. Bar 28 is rigidly connected by means of members 29 to spindle 30 which is pivoted in stationary brackets 31 to which is attached foot rest 32. Downward motion of bar 28 will cause rotation of spindle 30 thereby moving linkage member 33 of linkage assembly 10 in a downward direction. As member 33 descends it pulls with it linkage member 34; slide 35 is attached to member 34 and is, consequently, pulled down with it. Attached to slide 35 is a member 36 having two slots 37 and 38. Pivoted in each of slots 37 and 38 are hooked members 39 and 40. Hook 39 has a bar 41 rigidly secured thereto and extending therefrom. Hook 40 has an equivalent bar 42. Each of bars 41 and 42 extends over a shifter member 43. Depending upon the position of shifter 43 it will engage either bar 41 or bar 42 and thereby prevent one of the hooks 39 and 40 from engaging a T arm 44. The mechanism for selecting the position of shifter 43 will be fully described hereafter.

Referring now to Figures 6 and 20, T arm 44 pivots about hub 392 of yoke 46. Thus, if it be assumed that hook 40 is maintained out of engagement by shifter 43, hook 39 will engage in recess 372 of T arm 44 to pivot T arm 44 about hub 392. A pair of lugs 49 and 50 are secured to yoke 46 of clutch 6, and a small spring 51 is mounted in a recess 52 in T arm 44. Spring 51 applies pressure to a pair of small protruding elements (not shown) which extend one from each side of T arm 44 opposite lugs 49 and 50. Spring 51 and the small protruding elements are provided to take up lost motion of T arm 44 when it is pivoted against one of lugs 49 and 50. Thus, the amount of motion of T arm 44 is prevented from being critical, since lugs 49 and 50 will not be forced beyond their proper positions even if T arm 44 moves a somewhat excessive amount. It will now be seen that engagement of one of hooks 39 and 40 will cause pivoting of T arm 44 about hub 392 of yoke 46 and that T arm 44 will therefore apply pressure against one of lugs 49 and 50. When this occurs yoke 46 will be caused to swing about pin 53 which is secured in housing 54.

Referring now to Figures 5 and 6, clutch 6 is mounted to the bottom of table 55 by bolts 56 and bracket 57. Bracket 57 in turn is secured to housing 54 by any desired means such as welding, as shown at 425 in Figure 5. In the present structure another member 426 has been secured, as by welding, to the bottom of housing 54. While a single integral piece may be used it is preferred that side supporting elements 58 be mounted to member 426 by means of screws 59. A bearing 43 is mounted in yoke 46 by means of a pair of pins 45, firmly secured to yoke 46 as at 393. Slot 60, provided for pin 45 in sleeve 47 of bearing 48, is somewhat larger, in a vertical direction only, than the pin 45 itself. This will be noted in Figure 6 from the fact that the bottom of the pin 45 is shown as being spaced a definite distance from the bottom of the slot 60 in the outer race of the

bearing 48. This permits sliding of bearing 48 in a horizontal direction upon a tilting of yoke 46 about its two pivot pins 53. Main clutch spindle 61 has an enlarged portion 62 and at the center of this enlarged portion is a shoulder 63. Secured to portion 62 of shaft 61 by keyways 64 and 65 are elements 66 and 67 rotating with shaft 61. Element 66 has an annular brake surface 68 and element 67 has a corresponding brake surface 69. Elements 66 and 67 are biased together by a spring 70 mounted on a rod 71 threaded into element 66 as at 72. A brake member 73 is provided having surfaces 74 and 75 against which brake surfaces 68 and 69 are respectively adapted to bear. Member 73 is loosely mounted in housing 54 so that although rotation of the member is prevented it is free to slide a short distance toward either element 66 or element 67. The brake member 73 has its component parts secured together and is fastened to housing 54 by means of bolts 76. Member 73 has a generally triangular shape in its preferred embodiment.

When yoke 46 swings in one direction or the other bearing 48 will move with it. Assuming that hook 39 has engaged T arm 44 (Figure 20), the top part of the T arm will swing to the right and engage lug 49 which is secured to and extends from the clutch yoke 46. This will cause the top of yoke 46 to be swung to the right as viewed in Figure 5, and bearing 48 will slide to the right. Recesses 77 are provided in elements 66 and 67 in which the inner race 78 of bearing 48 rests. When bearing 48 slides to the right it will engage element 67 and push it to the right thereby disengaging brake surface 69 from surface 75 of member 73. It will also cause clutch surface 79 of element 67 to engage clutch surface 80 of pulley 24. Pulley 24 is mounted on shaft 61 by means of bearing 81, and the only connection between pulley 24 and shaft 61 must come through element 67. Because of spring 70 element 66 will tend to follow in the same direction as element 67. However, it will very soon abut against shoulder 63 on enlarged portion 62 of shaft 61 and be prevented thereby from further motion to the right. Since it is necessary for both elements 66 and 67 to have their braking surfaces 68 and 69 bearing against member 73 in order to obtain effective braking action there will be no effective braking action so long as bearing 48 is holding element 67 in engagement with pulley 24.

The clutch 6 will thereby transmit the motion of pulley 24 through shaft 61 to pulley 82 thereby causing it to rotate in a clockwise direction. As soon as a coil is fully wound the yoke 46 is returned to its upright position, as will be explained below, and spring 70 is thereby free to clamp elements 66 and 67 against member 73 to brake the shaft 61 and stop operation through the clutch 6. If lug 50 instead of lug 49 had been engaged by T arm 44, yoke 46 would have been swung to the left as viewed in Figure 5 and precisely the same sequence of operation would have occurred to engage element 66 with pulley 5 to cause pulley 82 to be rotated in a counterclockwise direction.

Returning now to Figure 20 it will be noted that at the top of T arm 44 there is a protrusion 83. After one of hooks 39 and 40 has caused T arm 44 to pivot, member 84, movable within a bushing 424 (see also Figures 4 and 6) and having beveled surfaces 85 descends, and by co-operating with protrusion 83 on T arm 44 prevents the T arm from returning to its normal position. This is necessary because of the fact that pressure by the operator on rod 28 is applied for only a very brief time and that upon release of pressure by the operator the T arm 44 will tend to return to its normal position as shown. Member 84 is used to prevent the T arm from so returning until the completion of a winding operation. Member 84 is pivoted to link 86 which in turn is rigidly fastened to a bar 87 which also carries a member 88 having a roller 89. Roller 89 is adapted to be engaged by a cam 90, whose operation will be explained below.

Movement of member 84 into a position where it prevents T arm 44 from returning to its normal position is governed by rotation of cam 90 (see also Figure 4). The rotation of spindle 91 on which cam 90 is mounted also controls the position of member 92 which is pivotally mounted at 93 on shifter 43, and which is movable within a bushing 422 as shown in Figure 6. It is by this means, which will also be explained in greater detail below, that shifter 43 selects which of hooks 39 and 40 will be prevented from engaging T arm 44. When member 92 is pushed downwardly, shifter 43 is pivoted about pin 394 (see Figures 2 and 6) in a counterclockwise direction to abut bar 41 and maintain hook 39 out of engagement with T arm 44; it will be noted that pin 394 may be formed as a screw arranged to hold a bushing 423 in place so that the member 43 is freely movable therearound; when member 92 is not being forced downward the position of shifter 43 is such that it prevents hook 40 from co-operating with T arm 44.

Referring now to Figures 4 and 20, the operation of counter 94 will be described. Counter 94 is provided for two main purposes. One is to stop the mechanism at the end of the winding operation in a precise fashion, and the other is to cause clutch 6 to reverse its operation the next time the machine is started by pressure on rod 28 of foot pedal 9, thereby reversing the coil winding operation. Worm gear 95 on spindle 91 meshes with a gear 96 to provide one rotation of worm gear 95 for a predetermined number of rotations of gear 96, such as 25. Gear 96 may be formed integrally with pulley 97 which is rotated by V belts 98. These belts in turn are moved by pulley 82 which is fastened to clutch shaft 61 by means of keyway 99. Thus, spindle 91 will be rotated once for each 25 turns of coil winding. Spindle 91 is supported towards its right end by a stationary bushing 373 maintained in a ring 100 which is firmly secured in opening 101 of housing 102. At the left end of spindle 91 there is a member 103 secured to housing 102 by screws 104 and having an internally threaded surface 105, there being 10 threads to the inch in the embodiment shown. Spindle 91 is correspondingly threaded, as at 106, so that rotation of spindle 91 will also cause axial movement in one direction or the other depending upon the direction of rotation of spindle 91. The other end of spindle 91 is threaded, as at 107 and mounted on threaded ends 108 of spindle 91 are cams 108 and 109. Since these cams are to remain in fixed relation to each other they may be made integrally, as in the present embodiment.

It has been shown that spindle 91 moves axially as it rotates. Because of this fact cams 108 and 109 will not be in contact with their cam followers 89 and 92 until axial movement brings them over the cam followers. When cam 108 contacts its follower 89 it will cause member 84 to be lifted to an inoperative position. When cam 109 contacts its follower 92 it will cause shifter 43 to be moved to a position where it prevents hook 39 from co-operating with T arm 44, and permits hook 40 to do so. Since a lifting of member 84 to an inoperative position will permit T arm 44 to return to its normal position and, consequently, brake clutch 6, the moment when cam 108 hits follower 89 determines the end of the coil winding operation in one direction. It will be seen from Figure 4 that cam 108 determines the number of coil turns in a counterclockwise direction while cam 90 determines the number of coil turns in a clockwise direction. The number of coil turns is determined by the distance between cams 108 and 90. Cam 108 is adjusted on threads 107 by means of nut 110, and a lock nut 111 is then used to lock the cam in place. The cam may be precisely located by means of graduated surfaces of parts 112 and 113. Part 112 is integral with nut 110 and cams 108 and 109; it has one reference mark as compared to 25 reference marks on the graduated surface of part 113. Part 113 is keyed to spindle 91 at 374

so as to slide thereon. Since spindle 91, through worm 95, rotates once for each 25 turns of coil, it will be seen that part 113, because of the 25 to 1 ratio of reference marks, permits the cams to be placed so accurately that the number of turns to be wound can be determined within one. This is achieved by turning part 112 relative to part 113 to the desired point, and then locking the parts in that position with lock nut 111. In view of the adjustability of cam 108 it is generally unnecessary to make any adjustments of cam 90, since it is the distance between the two cams surfaces that determines the number of turns that will be wound. However, for minor adjustments, up to one revolution, that may be desired for stopping the clockwise winding operation (as viewed from Figure 4) a slot 114 is provided in spindle 91. Through this slot extends a pin 115 which is secured at its outer end to cam 90 and at its inner end to an inner spindle 116 which may be rotated a small distance within spindle 91. Nut 117 is secured to inner spindle 116 and is turned to secure an adjustment of the position of cam 90. Member 375, keyed at 376 to spindle 91, acts as a reference member in the same manner as part 113. When such an adjustment has been effected nut 117 is locked in place by means of lock nut 118.

It will now be seen that an accurate counting device has been described which will determine precisely the number of turns of coil by means of an adjustment of the distance between cams 90 and 108, and which by means of cam 109 will determine whether the subsequent operation is to be in a clockwise or counterclockwise direction. Referring to this latter operation it will clearly be seen that at the end of a clockwise operation spindle 91 will have moved to the left so that cam 109 is pressing down on member 92. This in turn is pivoting shifter 43 to maintain hook 39 out of engagement with T arm 44. Thus when the next operation is commenced hook 40 will engage with T arm 44; as soon as there has been a slight motion of spindle 91 in the counterclockwise direction cam 109 will cease to engage member 92 and shifter 43 will return to its normal position. However, by this time hook 40 has already engaged T arm 44 so that T arm 44 is no longer in a position where it can co-operate with hook 39. T arm 44 will continue to be held in this manner because of member 84 which has descended to maintain the T arm in an off-center position. When the next operation is started the shifter 43 will be in its ordinary position preventing hook 40 from engagement with T arm 44. Since T arm 44 will have returned to its normal position because of the action of cam 90 pulling member 84 upward, hook 39 will be able to engage with the T arm 44 and the operation will consequently be in a counterclockwise direction.

Figure 4 shows the presence of prongs 119 on slide 35. These prongs are desirable to steady slide 35, since it forms the end of a relatively long straight member with link 34. This is effective by having prongs 119 slide into recesses 120 of clutch housing 54 thereby to provide a steady influence on slide 35. A tie bolt 121 connects prongs 119 of slide 35 together. Tie bolt 121 slides up and down in groove 122 in housing 54 thus in effect providing a safety limit on the amount of movement of slide 35.

Referring now to Figure 7 of the drawings, it will be seen that pulley 97 actuated by the V belts 98 is mounted on a core 123 by means of a bearing 124. Pulley 97 is secured to a drum 125 which, in the present embodiment, has been made integral with the pulley. Drum 125 rotates between the stationary core 123 and a housing 126. Drum 125 is supported at its left end by bearing 127 secured to housing 126, and at its right end by bearing 128 secured to core 123. A centrally located bearing 129 provides additional rotatable support with respect to housing 126. It will be seen that rotatable

drum 125 is held between the stationary housing 126 and the stationary core 123.

Referring to Figure 20A of the drawings, there is shown a preferred means of maintaining the core 123 stationary within the rotating drum 125. A ring gear 130 is nonrotatably secured to housing 126, by means of bolts 131. A gear 132 is secured to core 123 by means of a key 133. A gear 134 is rotatably secured to the drum by means of shaft 135 and bearing 136, and meshes with ring gear 130 as at 137. Gears 138 and 139 are fastened so as to be stationary relative to each other. They are rotatably secured to the drum by means of shaft 140 and bearing 141. Gear 138 meshes with gear 134, and gear 139 meshes with gear 132. Gears 132, 138 and 139 are so proportioned with respect to ring gear 130 and gear 132 that gear 132 is locked to the same rotational speed as gear 130. Since ring gear 130 is maintained stationary, gear 132 and consequently core 123 will also be maintained stationary.

Returning to Figure 7, a carriage, indicated generally at 16, is secured to and rotates with drum 125, and is mounted on a guide assembly 17. The back 143 of guide assembly 17 is removed a few thousandths of an inch from the front 144 of housing 126 in order to prevent rubbing. The wire which is to form the coils is led under wheel guide 14, rotatable about pin 145 and secured to drum 125 by extension 146. The wire then passes through tube 147, over groove 148 in shoe 149, over wheel 150 rotating about pin 151 and secured to carriage 16, and then through bushing 153. Carriage 16 is carried on a guide tube 154 which is part of guide assembly 17 and consequently, rotates with drum 125.

Referring again to Figure 20, it will be seen that a gear 155 is immovably secured to core 123. Guide tube 154 and the other parts of the guide assembly 17 are secured together at their outer ends by plate 157. Secured to this plate are stiffening rods 158 provided to add rigidity to the assembly, and lead screws 159 and 160 which will be further discussed below. Secured to guide tube 154 by means of a small housing 161 and a small shaft 162 rotatably mounted in housing 161 is a gear 163 securely fastened to shaft 162 and meshing with stationary gear 155. Gear 163, through shaft 162, turns gear 164 which in turn meshes with a gear 165, secured to lead screw 160. Gear 165 in turn meshes with gear 166 secured to the other lead screw 159. Thus, as the guide assembly 17 rotates with the drum around core 123 gear 163 meshes with gear 155 to turn lead screws 159 and 160.

Referring now to Figures 7, 11, 13 and 21 of the drawings, it will be seen that a tube like member 167 is provided on carriage 16. Member 167 is adapted to slide on guide tube 154. Extending downwardly from member 167 toward lead screws 159 and 160 are members 168 and 169. These members 168 and 169 have halfnuts 377 and 378 respectively formed in their ends. Halfnut 377 is adapted to engage screw 159 when carriage 16 is turned one way on tube 154 by wire tension, and halfnut 378 will engage screw 160 when the wire tension is in the opposite direction. Consequently, as gears 165 and 166 cause guide screws 159 and 160 to rotate, one of them will be engaged by one of the halfnuts 377 and 378 to cause carriage 16 to be carried along guide tube 154. No matter which of screws 159 and 160 is engaged by a halfnut, the threading is such as to cause carriage 16 to move toward drum 125.

Referring now to Figures 10 and 21 of the drawings, there is shown a hook 171 on which the wire 11 is snagged in order to hold it firm for the winding operation. Hook 171 may be secured in any desired manner to any stationary part of the machine; for instance, as shown in Figure 1, it may be arranged to extend from a stationary half ring member 297 whose function will be further

explained herebelow. Carriage 16 is shown in position ready to begin a winding operation when rotation of guide assembly 17 is started. Lead screws 159 and 160 will start turning about their own axes because of gears 165 and 166; thus, as the guide assembly 17 rotates with drum 125, carriage 16 will slowly move along one of lead screws 159 and 160 as the wire is wound on the wire forms, indicated generally at 172. It will be seen in Figure 21 that a flat hook member 379 is secured to an extension 380 of plate 157. Hook 379 is pivoted at 381; it is susceptible of being pivoted upwardly but is biased to the position shown by a spring (not shown). A latch member 382, adapted to co-operate with hook 379, is firmly secured to member 167 as shown at 383. When carriage 16 is caused to slide along tube 154 toward plate 157, as will be hereinafter explained, latch 382 will force hook 379 upward, and the two will then lock together. Because of this locking action, carriage 16 will be unable to slide along tube 154, when a winding operation is commenced, unless it turns to one side or the other to free latch 382 from hook 379. When carriage 16 turns it will engage one of lead screws 159 and 160. Thus, engagement with a lead screw is ensured from the very start of the operation, and the danger of missing even one of the predetermined number of turns is obviated.

Referring now to Figures 3, 8, 9, 10 and 20, it will be seen that since the coils of wire formed each time are eventually to be wound in six stator slots forming a 30 stator pole, with each coil passing thru two slots, coil form 172 has three different parts 173, 174 and 175 to take care of the three different coil lengths which will be necessary. It will be understood that the number of different parts, such as 173, 174 and 175, may be varied 35 depending upon the particular application of the improved coil winding machine of this invention, and that the present number has been arbitrarily selected for the present embodiment. It will be seen that the sides of the form 172 are progressively wider and that the tops 40 of the form are progressively higher, part 173 having merely a flat surface 176 around which the coils must go, part 174 having raised walls 177 over which the coils must go, and part 175 having still higher walls 178 for the coils.

Parts 180, 181 and 182 are provided with parts 175, 174 and 173 respectively and have sections 388, 389 and 390 respectively which fit within a slot 179 (Figure 10) provided substantially throughout the length of form 172, as shown. It will be clear that form 172 may, for economy 45 in manufacturing the machine, be formed of two originally separate parts each having a recess equivalent to half of the slot 179, and that these two parts may subsequently be integrally joined so that there will be formed the slot 179, as shown in Figure 10 for instance. In any 50 event, when assembly is complete, form 172 is in essence a unitary member having a slot which extends entirely thereacross and for substantially the entire length thereof but which terminates short of the outer end thereof. Referring now specifically to Figure 3 it will be seen that side parts 180, 181 and 182 (which in Figures 10, 11, 12 and 13 are sectioned off as shown to permit better understanding of these figures) are not of equal size but, to the contrary, increase in width with the height of the levels 176, 177 and 178 (Figure 10). All three parts 55 180, 181 and 182 have these varying dimensions for no more, however, than 180 degrees of a circle on each side of form 172 (see Figure 3). This is so in order to enable relatively thin sections 388, 389 and 390 (Figures 7 and 10), which are integral respectively with parts 180, 181 and 182, to fit within slot 179. These sections extend 60 into slot 179 for a short distance only for reasons to be hereafter explained. By fitting within slot 179, sections 388, 389 and 390 serve to align parts 180, 181 and 182, and to maintain them in their proper operative positions. Screw 386 which is threaded through sections 65 75

388 and 389, and secured to part 182, also helps maintain the parts in proper alignment.

The precise shape of parts 180, 181 and 182, to be further discussed below, of the coil form 172 appears most clearly in Figures 3 and 7. If parts 180, 181 and 182 of coil form 172 had evenly curved surfaces there would be undesirable bunching of the coils when they were later removed from the form 172. For this reason the curved side parts 180, 181 and 182 of form 172 have been given a hill and valley contour as shown at 384 (Figure 7). A single turn of wire will fit in each of the grooves 385; thus, when the coils are removed from form 172 there will be no bunching of the wires since the wires will have several different levels at which they will be placed. This will conserve space when they are finally placed in the stator slots, and will prevent undue crowding of the wires during the operation of removing them from form 172 and transporting them to the stator core, as will later be explained.

It will be understood that form 172 may be secured to core member 123 by any preferred means. In the present embodiment of the invention, however, the securing has been effected by providing the form 172 with a pair of flanges 431, one of which may be seen in dotted outline in Figure 7. Each flange fits over a side of projecting portion 427 of core 123. When the form and core are so positioned, a pair of bolts 428 and a pair of dowel pins 429 are inserted, as shown in Figure 7, through the projecting portion 427 and the flanges 431 so as to secure form 172 and core 123 together.

A comparison of Figures 10 and 11 will show the starting point of carriage 16 for the winding operation, its subsequent motion around coil form 172, and the consequent way in which the coils are wound. The number of turns per coil may easily be adjusted by means of screws 386 which appear in Figures 7 and 7A. A recess 387 is provided in each of the two parts 180 of form 172. By turning a screw 386 of which there are two, one being secured to each of parts 182 (Figure 7A), and holding part 181 stationary, part 181 can be caused to enter recess 387 thereby shortening the effective length of part 181 and increasing the effective length of part 182.

This effect is achieved by having thin section 389 of part 181 threadedly mounted on screw 386. Thin section 388 of part 180 is also threadedly mounted on screw 386. Therefore, by holding part 180 stationary while screw 386 is turned, the effective length of part 181 may be changed at the same time that the effective length of the sum of the three parts 180, 181 and 182 is being changed. In the present embodiment provision is made in form 172 for a total of 120 turns of wire. By means of adjusting screw 386 this number may be diminished, and the division between parts 180, 181 and 182 may be changed as desired. A recess 432 (Figure 7A) similar to recess 387 in part 180 is provided in part 181. In the same manner that part 181 could be made to enter recess 387 part 182 may be made to enter recess 432. It will be seen that this affords a further means of adjusting the number of coil turns to be wound.

Once coils have been wound, it is necessary to provide positive means of keeping the 3 different sizes separate and apart from each other when they are removed from form 172. Figures 8 and 9 best illustrate the means employed to achieve this separation. Referring now to Figure 8, there is shown a cross section through core 123. Mounted within core 123 in sliding relationship thereto are six plate-like divider members 183, 184 and 185. Each two sets of plates bearing the same number pass over opposite sides of a single size of formed coil. Thus plates 183, when they are slid forward, as will hereafter be explained, pass over the coil around part 173 of form 172, between walls 177 and 178. Plates 184 pass over the coil wound on part 174, between walls 178, and plates 185 pass over the coil wound on part

175 above the level of walls 178. The plates are parallel to the surface 176, and to the surfaces formed by the planes between walls 177 and 178 respectively, and are separated from each other only by the width of the wire forming the coil. This appears clearly in Figure 9 where plates 183, 184 and 185 have been moved to their most forward position over form 172. It will be seen that the coils on part 173 are firmly maintained in position by plates 183 and that the same is true of the other two groups. Surface 176 and walls 177 and 178 are preferably formed so that there is a very small angle, on the order of one degree, between them and the longitudinal axis of form 172. This angle is so provided that the two flat surfaces 176 of the form 172 are closer together at the outer end of the form 172 than at the inner end thereof. The taper provided for the walls 177 and 178 is similar; this effect is best seen in Figure 9 where it will be observed that the different surfaces of form 172 taper toward each other as the right edge of the figure is ap-

proached, in contradistinction to the slots 231 of injection head 20 (which will be further described below) which are formed substantially parallel to each other and to the longitudinal axis of form 172. Divider plates 183, 184, and 185 are also formed with a slight taper, that is, there is an angle of approximately one degree between the axis of each divider plate and the longitudinal axis of form 172. Thus, the divider plates are parallel to the surfaces of form 172 with which they cooperate. By providing the divider plates with a slight

30 taper, and by forming surface 176 and walls 177 and 178 so as to cooperate therewith, it will be seen that

when the divider plates slide forward, each one within

a coil section, they will tend to stress the coils slightly

by expanding them prior to their removal from form 172.

35 Returning now to Figure 8 it will be seen that a pin 186 passes through an opening 187 near the back of plates 183, 184 and 185. Pin 186 is actuated by a sleeve 188 which extends to the left through sleeve 354 to bearing 408 and collar 353 (see Figure 23), and is operated

40 in a fashion which will later be explained. As pin 186 is moved forward by sleeve 188 it carries with it plates

183, 184 and 185. When pin 186 reaches its forward-

most position, plates 183, 184 and 185 are in the position

shown in Figure 9.

45 Referring to Figure 12, the position of plates 185, 184 and 183 after full forward movement of pin 186 will be seen. The plates slide into divider plate locators 190. These are provided to add rigidity to the divider plates 183, 184 and 185 and to minimize the cantilever beam effect which results from the plates being supported only at their back end. Plate locators 190 are secured to a yoke 191 through which slides an injection head 20 which will be fully described below. Referring to Figure 9 again, the plate locators 190, secured to yoke 191 by

50 means of screws 192, will again clearly be seen.

Once divider plates 183, 184 and 185 are properly in place the next step is to slide the coils off form 172. This is effected, as shown in Figure 8, by means of pusher blades 193, 194 and 195. These blades fit in between

60 plates 183, 184 and 185; each one has a long slot 196 provided therein to permit divider plate pin 186 to move all the way forward before any motion is given to the pusher blades 193, 194 and 195. The blades are secured together as at 197 by rivets 198 and are kept at the

65 proper distance from each other at this point by spacer blocks 199. A pusher blade pin 200 is secured to a sleeve 201 which slides within sleeve 188 to move pin 200 back and forth. Since pin 186 will already have been moved forward to put plates 183, 184 and 185 into their operative positions, when sleeve 201 actuates pin 200 to move it forward with the pusher blades 193, 194 and 195 it will be able to do so freely without receiving interference from pin 186.

70 The shape of the pusher blades will be best understood by reference to Figure 22, in which a single pusher blade

195 is shown. It will be seen that slot 196 extends almost the entire length of pusher blade 195 to accommodate the sliding of divider plate pin 186.

It will be seen from Figure 7 that the hill and valley effect as shown at 384 in form 172 would make it impractical for pusher blades 193, 194 and 195 to remove the coils without a retraction of parts 180, 181 and 182 (this last not appearing in the figure) to a position where they will not interfere with the action of the pusher blades 193, 194 and 195. Retraction of the component parts 180, 181 and 182 of form 172 may be effected without fear of letting the wires droop since divider plates 183, 184 and 185 will already have been moved into position as previously described. Referring to Figures 7, 7A and 8, the retraction of the parts will now be described. As sleeve 188 is moved forward, carrying pin 186 to put the divider plates 183, 184 and 185 into operative position, the front 202 of sleeve 188 comes into contact with the back 203 of a block 204, which is arranged to slide back and forth within slot 179, thereby causing block 204 to move forward. The travel of block 204 is limited by a pin 205 fastened to the main part of form 172 and sliding in a slot 206 in block 204. Springs 207 are anchored in parts 208 of core 123 and press movable parts 210 inwardly against block 204. When block 204 is moved forward by part 202 of sleeve 188 cam surface 209 permits springs 207 to force movable parts 210 inwardly.

Referring now to Figure 7A, it will be seen that the stationary outer part of the form 172 supports a pair of pins 411 and that a mousetrap type spring 412 is mounted on each of these pins. One end 413 of each spring 412 is seated in a recess 414 in part 172, while the other end 415 of the spring fits into a slot 416 in part 182.

Block 204 is supported as its outer end 433 within an opening 417 in form 172. The block 204 is provided with surfaces 418 corresponding to surfaces 211 at the other end which are respectively adapted to engage inwardly projecting portions 419 respectively formed on parts 182. The block 204 is also provided with cam surfaces 420 corresponding to cam surfaces 209 at the other end. As the block moves to the right, as explained in connection with Figure 7, cam surfaces 420 will engage with surfaces 421 respectively formed on parts 182, and the springs 412 will force parts 182 inwardly as end 415 of each spring slides in a slot 416. When the block 204 is withdrawn toward the left, the engagement of camming surfaces 420 and 421 will force each part 182 outwardly against the action of spring 411.

It will now be seen that the block 204 ordinarily maintains the component parts 180, 181 and 182, in coil receiving position by preventing springs 207 from moving part 210 inwardly and by preventing springs 412 from moving the form parts 182 inwardly. Parts 210 are respectively attached to screws 386 by means of pins 395 which fit through extensions 212 of screws 386, and all three pairs of component parts 180, 181 and 182 are respectively secured to screws 386 as described above. Thus, when block 204 slides forward to the right, springs 207 are free to move parts 210 inwardly and springs 412 are free to move parts 182 inwardly; therefore, the component parts 180, 181 and 182 will all be moved in and removed from the coils which were wound on them.

It has been described before how parts 180, 181 and 182 all fit within slot 179 as at 388, 389 and 390. However, these component parts do not extend solidly through slot 179; instead, they only extend into slot 179 a short distance, as shown at 213 for part 180 and at 214 for part 181. Numerals 213 and 214 actually represent the shape of parts 388 and 389 within slot 179 on each side of block 204. Parts 388 and 389 do not fit snugly over blade 204 but are very loose thereon to permit the inward motion which will be caused by springs 207 when block 204 is moved forward by sleeve 188. The same

structure is present also in part 390, as shown in Fig. 7A.

Returning to Figures 8 and 13 (in the latter of which the pusher blades are fully forward), it will now be seen that, when pusher blades 193, 194 and 195 are moved forward between divider plates 183, 184 and 185 by pin 200, they will encounter no obstruction from the hill and valley structure as shown at 384 in Figure 7. Thus, blades 193, 194 and 195 will push the coils off form 172 as they move forward.

Pin 200 (Figure 8) has its ends terminating in square cross sections 215. As the pin starts to slide forward to move the pusher blades, and strip wire off form 172, ends 215 will slide in recesses 216 of rods 217. Secured to the fronts of these rods by screws 218 is a traverse reset ring 219 whose function will be explained later. After pin 200 has moved pusher blades 193, 194 and 195 forward a certain distance the ends 215 of pin 200 will contact the ends 220 of recesses 216 in rods 217. Pin 200 will then, while continuing to carry pusher blades 193, 194 and 195 forward, also carry traverse reset ring 219 forward. The total forward motion of traverse reset ring 219 will, of course, be less than that of pusher blades 193, 194 and 195 because of the lost motion achieved by the recesses 216 in rods 217.

Figure 13 shows that divider plates 183, 184 and 185 have been moved forward by pin 186. Ends 215 of pin 200 have moved traverse reset ring 219 into the position shown. It will now be seen why recesses 216 in rods 217 are necessary. Since pusher blades 193, 194 and 195 must force the coils into injection head 20 they must of necessity move a greater distance than traverse reset ring 219, whose function (explained below) is accomplished when it moves the carriage 16 to the end of guide assembly 17.

It will be seen that pivoted on member 167 of carriage 16 on a pin 221, there is a small lever 222. Referring momentarily to Figure 10 it will be seen that lever 222 has an essentially U-shaped cross section. When traverse ring 219 moves forward it hits the bottom 223 of lever 222. This causes the lever to pivot about pin 221 until its top sections 224 abut against stiffening rods 158. A stop 430 engageable with the bottom 223 is normally provided to take the greater part of the pressure off sections 224, thereby preventing them from scraping along rods 158.

As has been previously explained, members 168 and 169 projecting from members 167 (Figure 11) terminate in half nuts 377 and 378 which are adapted to mesh with the threads of lead screws 159 and 160. In the normal position of carriage 16 neither of the half nuts will engage either of lead screws 159 or 160. It is the pull of the wire that will cause either the half nut 377 to mesh with lead screw 159 or the half nut 378 to mesh with the lead screw 160 in order to advance the carriage 16 along guide assembly 17. The lead screw which will be engaged is a factor dependent upon whether rotation of drum 125 carrying guide assembly 17 is to be clockwise or counterclockwise. Since lever 222 is U-shaped, and pressure by traverse ring 219 at 223 on lever 222 will cause the lever to bear with equal pressure upon both stiffening rods 158 with the top parts of lever 224 and upon both sides of the stop 430 with the bottom part 223, part 167 of carriage 16 will be maintained in its intermediate position against any pull of the wire and neither of the half nuts 377 and 378 will engage either lead screw 159 or lead screw 160. Thus, when ends 215 of pin 200 force traverse ring 219 forward it will cause carriage 16 to be slipped along guide tube 154 to its outermost (and starting) position by means of member 167 without any interference from the threads on the half nuts 377 and 378. By this means, the forward motion of ring 219 causes carriage 16 to be returned to a position of readiness for the next winding operation.

It will be seen in Figure 13 that pusher blades 193, 194 and 195 will have forced the formed coils completely off the coil form 172. Thus the elements of the coil forming apparatus are ready to be retracted to a position where a winding operation may be recommenced, carriage 16 already having been put in such a position by traverse ring 219 pressing on the bottom 223 of lever 222.

Referring now to Figure 7 it will be seen that slots 391 are provided in sleeve 188 in order to provide space for pin 200, and prevent interference therefrom when sleeve 188 slides forward with pin 186 to move the divider plates 183, 184 and 185 forward. Subsequently, sleeve 201 is moved forward carrying pin 200 to move pusher blades 193, 194 and 195 forward. Upon retraction of sleeve 201, as will be further described below, pin 200 will be moved backward, carrying with it pusher blades 193, 194 and 195 and traverse rods 217 with traverse reset ring 219. Thus the pusher blades are returned to their position in core 123 and the traverse reset ring 219 is returned to its position at the front of core 123. Sleeve 188 will then be retracted, as will be further explained, pin 186 will be carried back, and divider plates 183, 184 and 185 will also be returned to their positions in core 123.

Referring now to Figures 8 and 7 it will be seen that within sleeve 201 there is a rod 226 having a shoulder at 227 beyond which its diameter is enlarged as at 228. Rod 226 extends forward and is secured to block 204 as at 229. This may be effected by having part 229 of block 204 enlarged and having rod 226 thereaded into it as at 230. When divider plate pin 186 has been moved back by sleeve 188 sufficiently to abut shoulder 227 of rod 226 it will carry rod 226 back with it as it continues to move. This will cause rod 226 to pull block 204 backward, and cam surfaces 209 will then force parts 210 outwardly against the action of springs 207. Parts 210 are pinned to screws 386 which are connected to the elements 180, 181 and 182 of form 172 and consequently will carry them outward to their proper positions for the next coil winding operation.

Thus all elements, the carriage, divider plates, pusher blades, and reset rings, are now ready to start the next coil winding operation.

Referring now to Figures 9 and 19, it will be seen that injection plug 20 has therein slots 231 in exact alignment with slots 232 which are formed between divider plates 183, 184 and 185. Thus, when pusher blades 193, 194 and 195 are forced along slots 232, as previously explained, and as shown in Figure 13, the formed coils 233 will be forced along slots 232 and into slots 231 in injection head 20, which is at that time in the position shown in Figure 9.

Referring now to Figure 19, the construction of the injection assembly will be described. It will be seen that the shell 234 of injection head 20 is considerably wider than the main body portion 235 in which slots 231 are formed. Spaces 236 and 237 are provided on each side of main body portion 235 to accommodate pusher shoes 238 and 239. Pusher shoes 238 and 239 are maintained together within injection head 20 by a pin 240 which fits in opening 241 in pusher shoe 238 and opening 242 in pusher shoe 239. Pin 240 also passes through a slot 243 provided in body 235 of injection head 20. Thus, the pusher shoes 238 and 239 are held together to move as a unit and are free to slide in injection head 20 to the extent permitted by the length of slot 243. Pin 240 has recesses 244 and pusher shoes 238 and 239 have corresponding openings 245. Screws 246 (Figures 16 and 17) pass through these openings to secure pin 240 and pusher shoes 238 and 239 together. Since the two pusher shoes are free to slide with pin 240 in injection head 20, to the extent permitted by slot 243, the injection of coils 233 into injection head 20 will force the shoes 238 and 239 to the back of the injection head 20.

The injection head has its ends closed by a pair of

caps 247 and 248. Looking now at cap 247, in Figure 19, it will be seen that it is fastened to injection head 20 by means of screws 290. A flange 249 closes the opening in the back of injection head 20; in flange 249 is an opening 250 whose purpose will be explained below. Accurate fastening of cap 247 to injection head 20 is aided by rabbet 251 in cover 234 of injection head 20.

At 252 there is represented a slot whose particular configuration and purpose will be described below. The details of cap 248 are the same as those of cap 247.

Pusher shoe 238 has a raised portion 253 which is topped by a surface 254, which preferably is sloping as shown. That part of the coil which will eventually form an end turn lies in front of raised portion 253 when pusher blades 193, 194 and 195 force the wire from form 172 into injection head 20 (Figure 13). Blades 255 of pusher shoes 238 and 239 are positioned so as to enter slots 231 in body 235, and to slide therein when the pusher shoe slides forward. Blades 255 project about a quarter of an inch into the sides of slots 231 in the present embodiment. Pusher shoe 239 has the same features as have just been described with respect to pusher shoe 238, the construction of course being exactly opposite so that the two shoes will have the same relation to body 235 when each of them is on an opposite side thereof. Cap 247 is secured by screws 256 to a flange 257 of a rod 258. Rod 258 is adapted to move back and forth axially as will hereafter be described and, hence, the entire injection assembly 20 which is secured 20 to rod 258 through cap 247 and flange 257 will have the same motion as rod 258. A housing 259 (see also Figure 1) is provided in which rod 258 slides. A large ring 260 is secured to housing 259 and has projecting therefrom two large pins 261. These pins are adapted to fit relatively loosely in openings 262 in yoke 191, thereby maintaining yoke 191 essentially stationary but without preventing a small amount of play which is necessary for divider plates 183, 184 and 185 to conveniently slide into divider plate locators 190.

Referring now particularly to Figure 20, and to Figures 1 and 2, the means provided for moving injection head 20 containing the formed coils to a position where they may be inserted in the stator will now be described.

A gear motor 21 is controlled by a switch assembly 22, gear motor 21 being so constructed as to cause a shaft 265 to rotate relatively slowly, at approximately one revolution per second in the present embodiment. It is only necessary to close a switch 264 momentarily in order to cause the motor 21 to operate, and motor 21 will continue to operate as controlled by switch assembly 22. Assembly 22 has a cam follower member 267 riding on a cam assembly 23 mounted on shaft 265 and having two diametrically opposed rises 269 so that follower 267 is depressed twice each revolution of shaft 265. When follower 267 is depressed, switch assembly 22 will then stop operation of motor 21. The construction of motor 21 and of switch assembly 22 may be that of any of several well known kinds and is not discussed further herein. Thus, shaft 265 will rotate half a revolution each time before it is stopped.

A pair of cams 270 and 271 are secured to shaft 265; as the shaft turns one half a revolution the two cams 270 and 271 will turn with it. Rotation of cam 271 will cause a follower (not shown) and a rack 272 attached to the follower to move to the right, as viewed in Figure 20. The force causing this motion will be discussed herebelow. Gear teeth 273 of rack 272 will then mesh with gear 274 causing gear 274 to rotate counterclockwise. This gear is secured by a shaft 275 to a larger gear 276 which rotates with gear 274. Rod 258 carrying the injection head 20 has gear teeth 277 cut therein meshing with gear 276. Since it has been shown that gear 274 will rotate counterclockwise when rack 272 moves to the right due to the configuration of cam 271, gear 276 will also rotate counterclockwise. This will cause rod

258 to be moved to the left, as viewed in Figure 20, carrying with it injection head 20. This motion is clearly illustrated in Figure 14. The gear diameters are such that half a revolution of shaft 265 will move injection head 20 to the precise point desired within the stator which is to be wound.

Returning now to cam 270 it is clear that it rotates with cam 271. However, because of the long dwell which is achieved by the shape of the cam, follower 278 will not cause rack 279 to move until after a certain amount of motion by rack 272 which is determined by the relative shapes of the cams. Once follower 278 has navigated the dwell 280 of cam 270, rack 279 will move to the right as seen in Figure 20. Shaft 281 is rotatably secured within housing 259 (Figure 1) but cannot move axially or sideways. Therefore, the above mentioned movements of rack 279 will cause teeth 282 of rack 279 to rotate gear 283 in a counterclockwise direction. Gears 284 and 285 also secured to shaft 281 will also rotate in a counterclockwise direction, thereby moving racks 286 and 287 to the left, as viewed in Figure 20. Rack 286 has a projection 288 at its left end and rack 287 has a corresponding projection 289 whose purpose will be explained below. At the moment that racks 286 and 287 move to the left, injection head 20 has been moved to a position directly in front of them so that projections 288 and 289 are directly in line with openings 250 in caps 247 and 248 (Figure 19). By this time injection head 20 has ceased to move because of dwell 291 on cam 271. Thus, as racks 286 and 287 continue to move, projections 288 and 289 will enter injection head 20 through openings 250 in caps 247 and 248.

Referring now to Figure 1, it will be seen that a base 291a is provided on which a pair of guide blocks 292 and 293 are mounted, block 292 being immovably secured to base 291a. Rack 286 moves back and forth within guide block 292 and rack 287 is similarly mounted within block 293.

Mounted in block 292 are guide rods 296; openings (not shown) are provided in block 293 to accommodate guide rods 296, and block 293 may thereby be caused to slide along rods 296. Secured to block 292 is a half ring member 297 having a solid back 298 and a cut away portion 299. A similar half ring member 300 (Figures 15, 16, 17 and 18) having a solid back 301 and a cut away portion 302 is secured to guide block 293. The stator to be wound fits within cut away portions 299 and 302 and is thus supported by the two half rings 297 and 300. Since block 293 is slidable on guide rods 296 half ring 300 may be adjusted with respect to half ring 297 to the proper distance to accommodate any width stator.

Still referring to Figure 1, there will be noticed spring housing members 303 and 304. These housings contain long coil springs 305 and 308 respectively (shown in part in Figure 20). The spring 305 within housing 303 bears at one end against end 396 (Figure 20) of rack 272, and at its other end against end 396 of the housing. The pressure of the spring on rack 272 may be adjusted by screw 307. The spring 308 within housing 304 is mounted in a similar manner, abutting against end 397 (Figure 20) of rack 279 at one end and against end 309 of housing 304 at the other end, the tension of the spring being adjustable by means of screw 310. These springs serve to make the followers on racks 272 and 279 follow cams 271 and 270 respectively, thereby causing injection head 20 to move into place within the stator to be wound and forcing racks 286 and 287 forward to cause the coils to be placed within the stator slots. Thus, the springs effectuate these operations; it will be observed that gear motor 21, by causing cams 270 and 271 to push the followers outwardly, effectuates the reverse operations.

Referring now to Figure 15 (also Figures 16, 17 and 18), there is shown a motor stator member 311 secured within half rings 297 and 300. It will be seen that half ring 300 is secured to guide block 293 by means of

screws 312 and dowel pins 313 to secure an accurate position of half ring 300 with respect to guide block 293. The same arrangements (not shown) may be provided for half ring 297 and guide block 292. It is within slots 314 of stator 311 that formed coils 233, held in slots 231 of injection head 20, are to be inserted.

In Figure 15, pusher shoe 239 is shown in the position to which coils 233 forced it when they were inserted into injection head 20 (Figure 13). Projection 288 of rack 286 is in position to strike pusher shoe 239. Secured to projection 288 by a pin 315 is a hook 316 whose function will be explained below. It will be noted that the front 317 of projection 288 is curved to fit the back of pusher shoe 239. Projection 289 has the same shape for the same purpose.

Referring now to Figure 16 of the drawings, it will be seen that the entrance 318 to cut away portion 299 and entrance 319 to cut away portion 302 are curved to permit easy entry of stator 311 into the cut away sections of half rings 297 and 300. Stator 311 is secured in the half rings as shown. It will also be seen that insulation 320 has been inserted in slots 314 previous to the winding operation. The position of hook 316 on projection 288 is such that, as projection 288 enters through opening 250 in cap 248, hook 316 will just clear the back 321 of pusher shoe 238. Hook 316 is biased to this position by a small spring 322 contained in projection 288. A cam surface 323 leads to a ridge 324 in groove 252 of cap 247. The purpose of ridge 324 and cam surface 323 will be explained hereafter. A baffle plate 325 is secured as at 326 to the front of guide block 292. Baffle plate 325 is provided to press down the end turns of any previously inserted coils to prevent injury to the end turns from pusher shoes 238 and 239.

Referring again to Figure 15, it will be seen that formed coil 233 does not extend all the way back in slots 231 of injection head 20. The centers of slots 231 extend back only as far as lines 398 (Figure 17) so that entry of coil 233 is limited thereby. However as shown in Figure 19, the sides of slots 231 extend all the way back in injection head 20 in order to accommodate blades 255 of pusher shoes 238 and 239. Thus, a starting point for blades 255 in slots 231 is provided without immediate interference from coils 233.

Referring now to Figure 17, movement of projection 288 has forced pusher shoe 239 forward to the extent shown. Blades 255 of pusher shoe 239, which have been resting in backs 327 of slots 231, have been brought forward with the pusher shoe, and have forced coils 233, which were resting in slots 231, forward out of injection head 20 and into slots 314, as shown in the three slots 328. The same sequence of events has occurred for shoe 238.

Referring now to Figure 18, it will be seen that surfaces 254 of raised portions 253 of shoes 238 and 239 are forcing end turns 329 of coils 233 well back toward the outer edge of stator 311. Cam surface 323 has forced hook 316 to pivot inwardly about pin 315 against the action of spring 322. Hook 316 is so proportioned that as it moves in it latches over back 321 of shoe 238 into a recess 330 which is provided at each end of pin 240. Hook 316 is maintained in this position by ridge 324 in groove 252 of cap 247. By this means, when racks 286 and 287 are forced to move back, hooks 316 will pull shoes 238 and 239 backward so that when projection head 20 is moved out of the bore of stator 311 there will be no interference occasioned by shoes 238 and 239 protruding out of injection head 20. Once hooks 316 reach cams surfaces 323 and move out, thereby disengaging racks 286 and 287 from shoes 238 and 239, the shoes have been pulled sufficiently far back into injection head 20 so that they will not protrude out of injection head 20 and interfere with its subsequent motion away from stator 311. By viewing Figures 17 and 18 it will be seen that the preformed coils 233 have been inserted into the slots of stator 311 and that this has been achieved in a

precise fashion by use of blades 255 operating in slots 231 of injection head 20 and by surfaces 254 on raised portions 253 of the shoes 238 and 239.

Referring again to Figure 20, when switch 264 is closed gear motor 21 will start to operate as before until a rise 269 on cam 23 is reached. Cams 270 and 271 will therefore rotate with shaft 265. The configuration of cams 270 and 271 is such that before any movement of rack 272 has been brought about, rack 279 will have been moved to the left as viewed in Figure 20. This will cause an action which is the reverse of what occurred before, in other words, racks 286 and 287 will be caused to move backwardly to the right as viewed in Figure 20. This will pull back shoes 238 and 239 into injection head 20, as explained before, and then, hooks 316 having been released from pressure by ridge 324, racks 286 and 287 will travel back and out of openings 250 in caps 247 and 248. By this time rotation of shaft 265 will have caused cam 271 to rotate past its dwell with respect to rack 272, and rack 272 will also be forced to the left as viewed in Figure 20. This also will cause an opposite motion to that which occurred before, that is, rod 258 will be moved to the right as viewed in Figure 20 and injection head 20 will be pulled out of stator 311 and back to its position in alignment with form 172.

Referring now to Figures 1, 2, 2A and 23, there is shown a handle 331 which by means of lever 332 and link 333 operates a standard 4-way air valve 334. Compressed air from an external source (not shown) is fed into valve 334 through inlet 335. Valve 334 is provided with pipes 336 and 337. Pipe 337 is connected as shown to cylinder 338, and pipe 336 is connected to the other end of the cylinder (see Figure 2A). It will be seen that pistons 340 and 341 are mounted respectively in cylinders 338 and 339 on piston rods 342 and 343. Piston rod 342 is secured to a projection 344 of a forklike member 345 which is mounted on a guide rod 346 so as to slide along it. Prongs 347 of fork 345 are mounted in a collar 348. Piston rod 343 is secured to a projection 349 on a fork 350 which slides on a guide rod 351 and has prongs 352 (see Figure 23) engaged in a collar 353. Large sleeve 354 is secured to and rotates with drum 125. Sleeve 354 contains rod 228, sleeve 201 and sleeve 188 in concentric relation (Figure 7). One or more slots 355 are provided in sleeve 354, and extend back past collars 348 and 353.

The two collars 348 and 353 rotate with sleeve 354 because of fastenings 356 and 357 which extend through collars 348 and 353 and slot 355 in sleeve 354. Referring now particularly to Figure 23, on the inside of sleeve 354 secured to fastening 357 is the outer race 407 of a bearing, indicated generally at 403. The inner race 409 of this bearing is immovably secured to the back end of sleeve 188 by any convenient arrangement, such as a cross-shaped keyway indicated generally at 410. Thus, while collar 353 will rotate with sleeve 354 and drum 125, because of bearing 403 and slot 355 in sleeve 354 sleeve 188 will slide with collar 353 but will not rotate. Since sleeve 188 operates divider plates 183, 184 and 185 these divider plates will be operated by piston rod 343 through fork 350 and collar 353. Fastening 356 extends through collar 348 and slot 355 in sleeve 354 and is secured to the outer race of another similar bearing (not shown). The inner race of this second bearing is immovably fastened to the back end of sleeve 201. Thus, sleeve 201 will slide with collar 348 but will not rotate therewith. Since sleeve 201 actuates the pusher blades 193, 194 and 195 they are originally operated by piston rod 342 acting through fork 345 and collar 348.

The valve operation will now be described. Returning to Figures 1 and 2, when handle 331 is pulled, a latch 363 will be released from its engagement with a member 361. This will connect pipe 336 to inlet 335, and pipe 337 will be connected to the valve outlet (not shown). This will cause piston 341 to slide forward to the right in cylinder

339 as air enters the left end through pipe 336 and leaves the right end through pipe 335. Piston 341 will, through piston rod 343, cause fork 350 to slide along guide rod 351, carrying with it collar 353. As explained above, this will cause divider plates 183, 184 and 185 to be moved to their operative positions. As fork 350 nears the end of its travel it strikes a small projection 339 which is secured to a spindle 400, thereby causing the spindle to rotate. Integral with the bottom of spindle 400 is an enlarged portion 359 to which a member 401 is rotatably and eccentrically attached. This member has secured to it a small rod 402 which is adapted to slide into a second 4-way valve 360. It will now be seen that rotation of spindle 400 will cause rod 402 to slide into valve 360.

Valve 360 has an inlet 403, an outlet (not shown), and a pair of pipes 404 and 405, the first of which leads to the front, or right, end of cylinder 338, and the second of which leads to the back of the cylinder (not shown). Movement of rod 402 to the right will connect pipe 405 with inlet 403, and pipe 404 to the outlet. This will cause piston 340 and piston rod 342 to move to the right, in the same manner piston 341 was actuated, thereby moving fork 345 and collar 348 and actuating pusher blades 193, 194 and 195 as explained above.

Arm 362 is secured to and extends from fork 345. Secured to this arm are previously mentioned member 361 and a second member 406. As fork 345 slides forward to its farthest position, member 406 will strike portion 359 and cause it to rotate, thereby moving rod 402 out of valve 360 because of the eccentric movement of member 401. Movement of rod 402 out of valve 360 connects pipe 405 to the air outlet and pipe 404 to air inlet 403. This will cause air to enter the front of cylinder 338 and leave the rear of the cylinder; piston 340 will slide back, taking with it fork 345 and collar 348. Pusher blades 193, 194 and 195 will, consequently, be returned to their starting positions within core 123.

As fork 345 reaches its starting position, member 361 will engage latch 363 which has returned to its engageable position because of the release of handle 331 by the operator. Engagement of latch 363 will connect pipe 336 to the valve outlet and pipe 337 to air inlet 335. Piston 341 will consequently slide back, fork 350 and collar 353 will be pulled back, and divider plates 183, 184 and 185 will be returned to their starting positions within core 123.

It will be noted that divider plates 183, 184 and 185, and pusher blades 193, 194 and 195 have been moved in the sequence described above, and are ready for another operation through a single manipulation of handle 331.

Referring now to Figure 2 of the drawings, it will be seen that wire tensioning device 12 comprises four guide wheels 364 rotatably mounted on a member 365. Member 365 is pivoted on pin 366 which is held in extension 367 of housing piece 368. A pin 369 is pivoted at 370 to member 365 and is loosely held at its other end in opening 371 of housing piece 368 so as to be able to slide back and forth. Means (not shown) bias pin 369 to the position shown in Figure 2. By means of this arrangement, the possibility of an undue amount of tension in wire 11 is avoided since pin 369 will slide into housing 368 when tension in wire 11 increases, and thereby lessen the tension. Such undue tension might, unless provision were made for it, result in faulty winding of wire 11 to make coils 233 on form 172.

Referring now to Figure 20, the operation of the machine will be described. Pressure by an operator on bar 28 of foot pedal 9 will actuate linkage 10 to cause one of hooks 40 and 39 to engage T arm 44. Engagement of T arm 44 by one or the other will cause it to pivot on hub 392 of yoke 46 and thereby cause connection of one of motors 1 and 2 to pulley 82. The selection of the motor is determined by which of hooks 39 and 40 engages T arm 44. This in turn is determined by the

position of shifter 43, as has been previously explained.

Assuming that the apparatus is in the position shown in Figure 20, shifter 43 will be in a position where it engages bar 42 to prevent engagement of hook 40 with T arm 44, and, consequently, hook 39 will engage the T arm. This will cause clutch 6 to connect motor 1 to pulley 82, as has been previously explained, and pulley 82 will rotate in a clockwise direction. This in turn, through belts 98, will cause pulley 97 and drum 125 to rotate also in a clockwise direction.

As is shown in Figure 7, guide assembly 17 is connected to rotate with drum 125. Assembly 17 rotates about a form 172 on which the coils are formed. Mounted on guide assembly 17 by means of a member 167 is wire carriage 16 which is adapted to move back and forth along guide assembly 17 as the assembly rotates about form 172. As has been previously explained, the lead screws 159 and 160 rotate on their axes as guide assembly 17 rotates about form 172. When a coil winding operation starts, carriage 16 will be in the position shown in Figure 10. Since assembly 17 commences to rotate in a clockwise direction wire 11, which is snagged to hook 171 (see Figure 13), will exert a pull in the opposite direction. Referring now also to Figure 21, it will be understood that as guide assembly 17 starts to rotate in a clockwise direction as viewed in Figure 20 (and in a counterclockwise direction as viewed in Figure 21) the wire will tend to exert an opposite pull. This will cause carriage 16 to pivot on guide tube 154 and half nut 377 of member 168 will engage lead screw 159. Since lead screw 159 is turning on its axis as the guide assembly rotates, the wire carriage 16 will move along the assembly 17 as the assembly 17 rotates about form 172. This will cause the wire 11 to be wound on form 172 as has been previously explained.

It now becomes necessary to remove the coils so formed from the form to make way for another coil winding operation. This is achieved by means of divider plates 183, 184 and 185 and pusher blades 193, 194 and 195 (see Figure 8). The divider plates and the pusher blades are actuated by the valve assembly and the sleeve construction shown in Figures 1 and 2, 2A and 23. Upon actuation of this valve assembly, the divider plates will slide forward to separate the coils wound on the three different levels 173, 184, and 175 of form 172 (see Figure 10). The valve assembly will then operate the pusher blades 193, 194 and 195 which will slide between the divider plates to push the formed coils off form 172 and into the slots 231 of injection heads 20. When the divider plates were moved forward the sleeve 188 which actuated them came forward to push a member 204 (see Figure 7) and thereby cause side members 180, 181 and 182 of form 172 to move inwardly, as has been explained, and thereby not interfere with the action of the pusher blades in removing the formed coils. As pin 200 moved the pusher blades forward it also moved forward a traverse reset ring 219 by means of a pair of rods 217. Thus, as the pusher blades move the formed coils from form 172 into the slots 231 of injection head 20, the traverse reset ring 219 has come up against the bottom 223 of a lever 222 mounted on wire carriage 16 and, as explained, has caused wire carriage 16 to slide along guide tube 154 free from engagement with either of lead screws 159 and 160, back to its starting position at the outer end of guide assembly 17. Thus, the actuation of the valve assembly of Figures 1, 2, 2A and 23 has caused the coils to be removed from form 172 and wire carriage 16 to be returned to a position of readiness for the next operation. As has been previously explained, the valve assembly will thereafter automatically cause retraction of the divider plates and the pusher blades into core 123, and of traverse reset ring 219 to the front of core 123.

It will also be observed that at the time cam 108 contacted cam follower 89 to stop the coil winding operation,

cam 109 contacted member 92 to move shifter 43 to a position where hook 39 would not engage T arm 44 on the next operation. Because of this, hook 40 will engage the T arm the next time the winding operation is commenced, and it will be the counterclockwise motion of motor 2, as viewed in Figure 20, that will be transmitted to guide assembly 17 so that the coils will be wound in the opposite direction. Also, spindle 91 of counter 94 will be caused to move in the opposite direction because of the opposite rotation and the operation will cease when cam 90 contacts cam follower 89. At this time the apparatus will be in the position first described and ready for another clockwise operation.

It will be recalled that the front coils have been moved into the slots 231 of injection head 20 which is presently positioned at the end of coil form 172. Closing of switch 264 will cause operation of gear motor 21 for half a revolution as controlled by cams 23. As has been explained, this will cause cams 270 and 271 to rotate with the half rotation of shaft 265. The shape of the cams causes cam 271 to be almost fully operated before cam 270 starts any actuation at all. Cam 271 will cause rod 258 and, consequently, injection head 20 to move to the left as previously described. This movement will continue as controlled by cam 271 until injection head 20 is in the position shown in Figure 14 within the stator 311 which is to be wound. Cam 270 will by then have completed its dwell and will cause racks 286 and 287 to move forward as previously explained. The two racks will move through openings 250 in caps 247 and 248 (Figure 19) and will force pusher shoes 238 and 239 forward within shell 234 of injection head 20. This action will also be seen by reference to Figures 15, 16, 17 and 18. As seen in Figures 15 and 16, racks 286 and 287 will move pusher shoes 238 and 239 forward. Blades 255 and raised portions 253 on the pusher shoes will force the coils out of slots 231 of injection head 20 and into the slots 314 of stator 311.

Stator 311 is held in a pair of half ring members 297 and 300, half ring 300 being movably adjustable to accommodate any width stator. After the pusher shoes have reached the position shown by Figure 18 another actuation of switch 264 will cause another half rotation of shaft 265 by gear motor 21. Cams 270 and 271 are so shaped that the reverse of what happened before will now occur. First, racks 286 and 287 will be moved back to their previous position pulling shoes 238 and 239 back into injection head 20 as has been explained; then rod 258 and injection head 20 will move to the right as seen in Figure 20 until injection head 20 is again opposite the end of form 172 and in position for another coil winding operation. It will clearly be seen that at the same time that formed coils are being inserted into stator 311 another coil is being wound on form 172. Thus, the machine performs a double function in an efficient manner by having the different elements interconnected for cooperative action yet separated enough so that two different functions, coil winding and coil insertion, may be performed at the same time in different parts of the machine.

It will be understood that while manual operation has been described for the actuation of linkage 10, the valve assembly of Figures 1, 2 and 2A, and for gear motor 21, these functions may well be automated in any one of many well known ways without departing from the spirit and scope of the invention. It will be further understood that while a specific valve assembly has been described for the operation of the pusher blades and divider plates of the machine, other means may be substituted to cause precisely the same functions to be performed in the same way. This is also true as to clutch 6 and linkage 10 which have been described in detail in order to provide a full comprehension of the overall working of the machine but which are clearly subject to

modification without departing from the scope of the invention of the machine as a whole.

It is clear from the above description that this invention provides a novel machine for winding coils and then inserting them in the field member of a dynamo electric machine using a hitherto unused sequence of operation. It may further be seen from the above description that the coil winding operation is quickly and accurately performed, and that it may be carried on at the same time as the insertion of another coil into the slots of a field member. Another feature which has been brought out is the accurate method of insertion of the coils into the field member slots in order to achieve maximum use of the space within the slots without cross-overs or other damaging factors being present.

While this invention has been explained by describing a particular embodiment thereof it will be apparent that improvements and modifications may be made without departing from the scope of the invention as defined in the appended claims.

What I claim as new and desire to secure by Letters Patent of the United States is:

1. In a machine for winding electric motor coils a coil form, a pair of electric motors operating in opposite directions, wire carrying means adapted to be rotated by said motor means alternately about said form to thereby form coils thereon, a clutch adapted selectively to connect said wire carrying means to one of said electric motors thereby to vary the direction of rotation of said wire carrying means, counter means for determining the number of rotations of said wire carrying means about said form during a single coil forming operation, means for removing the formed coils from said form, and means for subsequently inserting the formed coils into the slots of a stator.

2. In a machine for winding electric motor coils a coil form; a pair of electric motors adapted to continuously operate in opposite directions during operation of said winding machine; coil forming means comprising a drum rotatable alternately by each of said electric motors, guide means secured to said drum, a wire carriage mounted on said guide means to rotate therewith and co-operable therewith to move axially thereof, said guide assembly extending parallel to said coil form whereby rotation of said guide assembly about said coil form will cause said wire carriage to wind coils on said form; means for removing the formed coils from said form; and means for subsequently inserting the formed coils into the slots of a stator.

3. A machine for winding electric motor coils comprising a pair of electric motors rotating in reverse directions continuously during operation of said machine, rotatable coil forming means adapted to be selectively operated by each of said motors, clutch and brake means adapted to select one of said motors to operate said coil forming means for a coil forming operation, said clutch and brake means comprising a pair of movable brake and clutch members, means biasing said brake and clutch members together, each of said brake and clutch members being adapted to connect said coil forming means to be operated by one of said motors, counter means adapted to select one of said brake and clutch members to cause rotation of said coil forming means by one of said motors, means operated by movement of each of said brake and clutch members to operatively connect one of said motors to said coil forming means to cause said coil forming means to operate in the same direction as said one selected motor, means connected with said counter means to disconnect said coil forming means from said selected motor after a predetermined number of coils have been wound, and means for subsequently inserting the formed coils into the slots of a stator.

4. In a machine for winding electric motor coils, a coil form; means for forming coils on said form; counter means for determining the number of turns of coil to be

wound during a single operation comprising a stationary nut, a spindle connected to rotate during said coil forming operation, said spindle being threaded into said nut whereby said spindle moves axially as it rotates, a pair of cams mounted on said spindle and axially displaced from each other; a brake mechanism; and linkage means operated by said cams and connected to said brake mechanism to cause positive operation of said brake mechanism after a predetermined number of rotations of said spindle.

5. In a machine for winding electric motor coils, a coil form; coil forming means adapted to rotate about said coil form; a pair of motors rotating in opposite directions continuously during operation of said machine; a combination clutch and brake mechanism adapted to selectively connect one of said motors to operate said rotatable coil forming means, said clutch and brake mechanism comprising a pin, a yoke pivotable about said pin, a pair of brake and clutch members adapted to be moved one at a time by said yoke, a pair of lugs secured to and extending from said yoke and a pivotable member positioned between said lugs, said pivotable member being adapted to engage one of said lugs when it pivots to thereby pivot said yoke and move one of said brake and clutch members, each of said brake and clutch members being adapted when moved by said yoke to connect one of said motors to operate said coil forming means; and counter means cooperable with said pivotable member to determine the direction in which said member is to pivot thereby determining the direction of rotation of said coil forming means.

6. The machine of claim 5 wherein there are provided a pair of hooks, each of said hooks being engageable with said pivotable member to tilt the same and thereby select one of said motors to operate said coil forming means, said counter means being selectively co-operable with each of said hooks to maintain it out of engagement with said member whereby the other of said hooks is free to engage said member to determine the direction of rotation of said coil forming means.

7. In a machine for winding electric motor coils a coil form; coil forming means adapted to rotate about said form; a pair of electric motors adapted to rotate continuously in opposite directions during operation of said machine; means for selectively connecting one of said motors to drive said coil forming means; and means for determining the operation of said selective means comprising a stationary nut, a spindle threaded into said nut and adapted to rotate in one direction during rotation of said coil forming means by one of said motors and to rotate in the other direction during rotation of said coil forming means by the other of said motors, said spindle having an axial movement during rotation caused by its engagement with said nut, a pair of axially displaced cams on said spindle, at least one of said cams being adjustable axially of said spindle, at least one of said cams being rotatably adjustable on said spindle, each of said cams being operative after a predetermined number of rotations of said spindle in one direction to disconnect said selective means from the selected motor.

8. The machine of claim 7 including a third cam secured to one of said cams, said third cam being operative after said predetermined number of rotations to positively prevent said selective means from connecting one of said motors to said coil forming means thereby causing said selective means to connect the other of said motors to said coil forming means.

9. The machine of claim 7 including a third cam secured to that one of said first two cams which is axially adjustable, said third cam being operative after said predetermined number of rotations to positively prevent said selective means from connecting one of said motors to said coil forming means thereby causing said selective means to connect the other of said motors to said coil forming means.

10. The machine of claim 7 including a third cam secured to one of said cams, and positive means arranged to cause said selective means to tend always to engage a specific one of said motors upon actuation, said third cam being operative after said predetermined number of revolutions to prevent engagement of said one specific motor and to provide for engagement of the other of said motors.

11. The machine of claim 7 including adjustment means for one of said cams including a second spindle within and extending beyond said first spindle, said first spindle having a slot therein, and a pin extending through said slot and securing said second spindle to said one cam whereby rotation of said second spindle relative to said first spindle will cause rotation of said one cam relative to said first spindle to effect an adjustment of said one cam.

12. In a machine for winding electric motor coils driving means, a coil form; coil forming means; and means connecting said driving means to said coil forming means to cause the same to rotate said coil forming means comprising a hollow drum secured to said connecting means to rotate therewith, a guide assembly secured to said drum and extending parallel to said coil form and being spaced therefrom so as to rotate thereabout, said guide assembly comprising a guide tube and at least one lead screw both extending parallel to said form means for rotating said lead screw upon its axis as said assembly rotates, and a wire carriage mounted on said guide comprising a section slidably cooperable with said guide tube, said wire carriage further comprising at least one threaded member adapted to cooperate with said lead screw to cause said wire carriage to move axially of said guide assembly as it rotates therewith.

13. In a machine for winding electric motor coils, driving means; a coil form; coil forming means; and means connecting said driving means to said coil forming means to cause the same to rotate, said coil forming means comprising a hollow drum secured to said connecting means to rotate therewith, wire guide means secured to said drum, a guide assembly secured to said drum and extending parallel to said coil form and being spaced therefrom so as to rotate thereabout, said guide assembly comprising a guide tube and a pair of lead screws extending parallel to said form, means for rotating said lead screws upon their axes upon rotation of said assembly, and a wire carriage comprising a tube section slidably encircling said guide tube, said wire carriage further comprising a pair of half nuts engageable respectively with said lead screws, said carriage being pivotable upon said guide tube upon rotation of said guide assembly in either direction in response to tension of wire occasioned by said rotation whereby one of said half nuts and one of said lead screws will cooperate to cause said carriage to move axially of said assembly as said assembly rotates about said form.

14. In a machine for winding electric motor coils, a form for receiving said coils comprising a block having a pair of flat surfaces, a slot extending through said block from side to side for substantially the entire length thereof, curved means projecting from said slot on each side to thereby provide a side support for coils formed on said form, means biasing said curved means toward said slot, means for preventing said biasing means from moving said curved means, and means for counteracting said preventing means to permit said biasing means to retract said curved means toward said slot whereby after a winding operation said counteracting means will permit said curved means to withdraw from contact with the coils wound thereon to facilitate removal of said coils from said form.

15. In a machine for winding electric motor coils, a form for receiving said coils comprising a block having a pair of flat surfaces, walls raised on the edges of said flat surfaces for a portion of their length, said walls being in sections and each section being of greater height than

the previous section, a slot extending thru said block from side to side for substantially the entire length thereof, a plurality of curved means projecting from said slot on each side thereby to provide a side support for coils formed on said form, said curved means projecting out of said slot increasingly as said wall section above said curved means increases in height whereby said wall sections and said curved means cause coils wound on said form to be of varying size dependent upon their location thereon, means biasing said curved means toward said slot, means for preventing said biasing means from moving said curved means, and means for counteracting said preventing means to permit said biasing means to retract said curved means towards said slot whereby after a winding operation said counteracting means will permit said curved means to withdraw from contact with the coils wound thereon to facilitate removal of said coils from said form.

16. In a machine for winding electric motor coils, a form for receiving said coils comprising a block having a pair of flat surfaces, walls raised on the edges of said flat surfaces for a portion of their length, said walls being in sections and each section being of greater height than the previous section, a slot extending through said block from side to side for substantially the entire length thereof, a plurality of curved means projecting from said slot on each side to thereby provide a side support for coils formed on said form, said curved means projecting out of said slot increasingly as said wall sections above and below said curved means increase in height whereby said wall sections and said curved means cause coils wound on said form to be of varying size dependent upon their location thereon, said curved means having longitudinal cross sections in the shape of curved alternate hills and valleys, the curvature of said hills and valleys being broken by equi-spaced grooves each adapted to receive a single strand of wire.

17. In a machine for winding electric motor coils, a coil form, means for forming coils of different sizes thereon, means for removing said coils comprising dividing means adapted to slide between said coils, and means adapted to subsequently slide between said dividing means against said coils whereby said coils are pushed off said form in a predetermined order and in a predetermined direction.

18. In a machine for winding electric motor coils, a coil form; means for forming coils of different sizes thereon; and means for removing said coils comprising a stationary core adjacent one end of said form, divider plates slidably mounted in said core and adapted to slide partially out of said core and over said form between said coils, and pusher blades slidably mounted in said core alternately with said divider plates and adapted to slide partially out of said core and over said form between said divider plates against said coils whereby said coils are pushed off said form in a predetermined order and in a predetermined direction.

19. In a machine for winding electric motor coils, a coil form; means for forming coils of different sizes thereon; and means for removing said coils comprising a stationary core adjacent one end of said form, divider plates slidably mounted in said core and adapted to slide partially out of said core and over said form between said coils, said divider plates being in two vertically displaced groups, a pin for actuating said divider plates connecting them all together at their rear, pusher blades slidably mounted in said core, said pusher blades being located one between each two of said divider plates and one on the outside of each group of said divider plates and being adapted to slide partially out of said core and over said form between said divider plates against said coils whereby said coils are pushed off said form in a predetermined order and in a predetermined direction, and a pin for actuating said pusher blades connecting them all together at their rear.

20. In a machine of claim 19, a sleeve extending parallel to said divider plates and connected at one end to said divider plate pin, and a fluid actuated cylinder comprising a piston and a piston rod, said sleeve being connected at its other end to said piston rod whereby admittance of fluid to said cylinder determines movement of said divider plates.

21. In a machine of claim 19, a sleeve extending parallel to said divider plates and connected at one end to said divider plate pin, and a fluid actuated cylinder comprising a piston and a piston rod, said sleeve being connected at its other end to said piston rod whereby admittance of fluid to said cylinder determines movement of said divider plates; and a second sleeve extending parallel to said pusher blades and concentrically with said first mentioned sleeve, said second sleeve being connected at one end to said pusher blade pin, and a second fluid actuated cylinder comprising a piston and a piston rod, said second sleeve being connected at its other end to the piston rod of said second cylinder whereby admittance of fluid to said second cylinder determines movement of said pusher blades.

22. In a machine for winding electric motor coils, a coil form, coil forming means rotatable about said coil form comprising a guide assembly, a wire carriage slidably mounted on said guide assembly and adapted to rotate therewith and to move axially therealong during rotation of said assembly whereby said wire carriage moves from one end of said guide assembly to the other during a coil forming operation, engageable means extending from said carriage, a stationary core adjacent one end of said form, means slidably mounted in said core and adapted upon actuation to co-operate with said engageable means to slide said carriage along said guide assembly to the first end thereof, and means for actuating said slidably mounted means.

23. In a machine for winding electric motor coils, a coil form; coil forming means rotatable about said coil form comprising a guide assembly comprising a pair of lead screws extending parallel to said form, a wire carriage slidably mounted on said guide assembly and adapted to rotate therewith, said carriage being pivotable on said guide assembly and comprising a pair of half nuts engageable respectively with said lead screws, both said lead screws being mounted on said carriage between said half nuts being mounted on said carriage, pivoting of said carriage will cause one of said half nuts to engage one of said lead screws to cause said carriage to move axially along said guide assembly during rotation thereof, U-shaped lever means pivotable on said carriage and having both sides extending around a side of said carriage, and stop means for said lever secured to said carriage; a stationary core adjacent one end of said form; means slidably mounted in said core and adapted upon actuation to strike the bottom of said lever whereby said carriage is positively centered to prevent engagement of either of said half nuts with either of said lead screws whereby further movement of said slideable means will cause said carriage to be slid along said guide assembly to the first end thereof; and means for actuating said slidably mounted means.

24. The apparatus of claim 23 wherein said slideable means comprise a pair of rods extending parallel to said guide assembly and a ring mounted on the end of said rods toward said guide assembly, said ring being concentric with the circle of rotation of said guide assembly and being adapted to strike the bottom of said lever upon being axially motivated theretoward.

25. The apparatus of claim 23 wherein said slideable means comprise a pair of rods extending parallel to said guide assembly and a ring mounted on the end of said rods toward said guide assembly, said ring being concentric with the circle of rotation of said guide assembly and being adapted to strike the bottom of said lever upon

being axially motivated theretoward; said apparatus further comprising a pin engaging said rods at their ends remote from said guide assembly to cause them to move as a unit, said pin being slidably mounted within said core, and sleeve means connecting said pin to said actuating means.

26. In a machine for winding electric motor coils, a coil form, means for forming coils thereon, means for removing the formed coils therefrom, and means for receiving said formed coils comprising a substantially cylindrical member having a substantially solid body portion, said member having parallel slots extending from the surface into said body portion, each slot being in the same plane as a part of one of said formed coils, said member being adjacent an end of said coil form when said formed coils are removed from said form whereby a part of each of said formed coils enters one of said slots upon removal of said formed coils from said form.

27. In a machine for winding electric motor coils, a coil form; means for forming coils thereon; means for sliding the formed coils off said form; and means for receiving and removing said formed coils comprising a substantially cylindrical member comprising a shell, said member being positioned opposite and adjacent an end of said form during removal of said formed coils therefrom, said member further comprising a substantially solid body portion opposite said form, said body portion having a plurality of parallel slots therein, each of said slots being in the same plane as a part of one of said formed coils when said formed coils are removed from said form whereby a part of each of said formed coils enters one of said slots upon removal thereof from said form, and means to thereafter move said member away from said form.

28. In a machine for winding electric motor coils, a coil form; means for sliding formed coils off said form; means for receiving said coils comprising a substantially cylindrical member having slots therein adapted to receive said coils from said form, said member including a shell and a body portion within said shell, said shell extending past said body portion on each side thereof thereby to provide spaces within said shell on each side of said body portion, said coils extending into said spaces when in said slots, and a pair of pusher members located one in each of said spaces, said pusher members being slidably mounted to slide back and forth in said spaces; means for moving said member after reception of said coils in said slots to a position adjacent a stator to be wound; and means for causing said pusher members to slide forward in said shell to eject said coils from said member and position said coils in said stator.

29. The apparatus of claim 28 including blades formed on said pusher members, said blades extending a relatively short distance into said slots from each of said pusher members on each side of said body portion, said blades being slideable in said slots when said pusher members slide in said shell thereby to more effectively eject said coils from said member.

30. The apparatus of claim 28 including blades formed on said pusher members, said blades extending a relatively short distance into said slots from each of said pusher members on each side of said body portion member, said blades being slideable in said slots when said pusher members slide in said shell thereby to more effectively eject said coils from said member; said apparatus further including a raised surface on the front of each of said pusher members, said raised surfaces being sloped so that said surfaces are increasingly raised as the distance from said body portion increases thereby to more effectively guide said coils into a wound position on said stator.

31. In a machine for winding electric motor coils, a coil form; means for sliding formed coils off said form;

means for receiving said coils comprising a substantially cylindrical member having a body portion with slots therein adapted to receive said coils from said form, said member having a shell extending past said body portion on each side thereby to provide spaces, said coils extending into said spaces when in said slots, a pair of pusher members located one in each of said spaces, and a pair of caps positioned one at each end of said shell and secured thereto, said pusher members each being slidably mounted between said body portion and one of said caps so as to slide back and forth in the space so formed; means for moving said member after reception of said coils in said slots to a position adjacent a stator to be wound, said shell having an opening behind each of said pusher members; and means adapted to enter each of said openings to force said pusher shoes to slide forward in said shell to eject said coils from said member and wind said coils on said stator.

32. In a machine for winding electric motor coils, means for transporting formed coils to a position adjacent a stator to be wound, said means comprising a member having a shell and a slotted body portion for holding said coils; slideable means within said shell on each side of said body portion adapted to slide forward to eject said coils from said body portion and insert said coils in the slots of said stator; and means for sliding said slideable means forward comprising a pair of rack members, rotatable gear means engaged with said rack members to cause said rack members to move forward in a substantially straight line, each of said rack members having an end arranged to enter said shell and engage said slideable means upon being moved by said gear means thereby to cause said slideable means to move forward to eject said coils from said member and to insert said coils in the slots of said stator.

33. In a machine for winding electric motor coils, means for transporting preformed coils to a stator to be wound; means for subsequently inserting said coils into the slots of said stator; and means for operating both of said means in said sequence comprising an electric motor, a shaft rotatable by said motor, a pair of cams secured to said shaft, a pair of cam followers riding on said cams respectively, means secured to one of said followers and adapted to operate said transporting means in response to a predetermined amount of rotation of said shaft, and means secured to the other of said followers and adapted to operate said inserting means upon a second predetermined amount of rotation of said shaft, said cams being so formed as to cause said operation of said transporting means to be substantially completed before said operation of said inserting means commences.

34. The apparatus of claim 33 including additional cam means on said shaft, and circuit breaking means operated by said additional cam means to open the circuit to said motor, said additional cam means being so formed as to cause the circuit to said motor to be opened after each half revolution of said shaft.

35. In a machine for winding electric motor coils, means for transporting preformed coils to a stator to be wound; means for subsequently inserting said coils into the slots of said stator to form a pole; means for operating both of said means in said sequence comprising an electric motor, a shaft rotatable by said motor, a pair of cams secured to said shaft, a pair of cam followers riding on said cams respectively, a gear rack secured to one of said followers, a gear means connecting said rack and said transporting means to cause said transporting means to carry said coils to said core upon a predetermined amount of rotation of said shaft, spring means biasing said one follower against said one cam; a second gear rack secured to the other of said followers, second gear means connecting said second rack to said inserting means to cause said inserting means to operate upon a second predetermined amount of rotation of said shaft, and

spring means biasing said other follower against said other cam.

36. The apparatus of claim 35 including additional cam means on said shaft, and circuit breaking means operated by said additional cam means to open the circuit to said motor, said additional cam means being so formed as to cause the circuit to said motor to be opened after each half revolution of said shaft.

37. In a machine for winding electric motor coils, means for transporting preformed coils to a stator to be wound; means for subsequently inserting said coils into the slots of said stator to form a pole; means for operating both of said means in said sequence comprising an electric motor, a shaft rotatable by said motor, means cooperable with said shaft for limiting continued operation of said motor to one half revolution of said shaft, cam means secured to said shaft and connected to said transporting means and said inserting means to cause operation thereof in said sequence upon rotation by said shaft of a half revolution, said cam means being so formed as to cause said transporting means and said inserting means to return to the positions occupied before said operation in reverse sequence upon a subsequent rotation by said shaft of a half revolution.

38. In a machine for winding electric motor coils, means for transporting preformed coils to a position adjacent a stator to be wound, said means comprising a member having a body portion with slots therein adapted to receive and hold said coils, said member comprising a shell extending beyond said member on each side thereby to provide spaces, said coils extending into said spaces when in said slots, a pair of pusher members located one in each of said spaces, a pair of caps positioned one at each end of said shell and secured thereto, a flange on each of said caps extending along the back of said shell, each of said flanges having an opening therein behind one of said pusher members, said pusher members each being slidably mounted in said shell between said body portion and one of said caps so as to slide back and forth in said spaces, means adapted to enter said openings to force said pusher members forward when said coils are adjacent said stator thereby to cause insertion of said coils in said stator, latch means secured to each of said entering means, a spring biasing each of said latch means outwardly, a camming surface in each of said caps adapted to force said latch means inwardly toward said body portion upon operation of said means adapted to enter said openings, said pusher members each having a recess adapted to receive one of said latch means when the same is forced inwardly, means connected to said means adapted to enter said openings to withdraw the same out of said openings after said coils are inserted in said stator, each of said latch means remaining in each of said recesses until said latch means have been withdrawn past said camming surfaces whereby said pusher members are pulled back by said latch means an amount sufficient to prevent projecting of said pusher members outside said member.

39. In a machine for winding electric motor coils, a coil form, means rotatable relative to said form to form coils thereon, means slidably engaging said form for removing the formed coils therefrom, and means for receiving said formed coils positioned adjacent an end of said coil form during removal of said formed coils from said form, said receiving means comprising a member including a body portion having a surface facing said coil form when said receiving means are adjacent the end thereof, said body portion having slots formed therein extending from said surface, each of said slots being in the same plane as a part of one of said formed coils whereby a part of each of said formed coils enters one of said slots upon removal of said formed coils from said form.
